UNITED STATES PATENT OFFICE.

DAVID G. SMYTH, OF HARTFORD, CONNECTICUT.

MACHINE FOR FEEDING AND ASSEMBLING SIGNATURES.

No. 909,701.

Specification of Letters Patent.

Patented Jan. 12, 1909.

Application filed September 12, 1907. Serial No. 392,457.

To all whom it may concern:

Be it known that I, DAVID G. SMYTH, a citizen of the United States, residing at Hartford, in the county of Hartford and State of Connecticut, have invented an Improvement in Machines for Feeding and Assembling Signatures, of which the following is a specification.

My invention relates to devices for gathering signatures and presenting the same in successive order to be placed upon the sheet holding bar of machines for sewing the same into book form, the art of which machines is exemplified in the U. S. patents granted to David McConnell Smyth, No. 220,312, October 7th, 1879; No. 250,987 and No. 250,991, granted December 13th, 1881, and also Letters Patent of the United States granted to Reynolds and Jacobs, No. 435,613, September 2d, 1890.

Heretofore it has been usual to gather or assemble the signatures in successive order for each book, either by a suitable machine or by hand, and to place the piles of signatures thus gathered on a suitable table, from which the signatures are taken one at a time by hand and placed upon the sheet holding bar which moves them up to the sewing mechanism and in connection with this operation it is usual to examine and count the signatures so as to prove them up before the sewing is performed, so as to reduce to a minimum the liability of any error.

In the device of my improvement, the signatures are assembled one at a time as the sewing is carried on, the signatures appearing in gathered form only after they have been delivered by the sheet holding bar and sewed together. The signatures composing each book are separated one at a time and in consecutive order from the various piles in which they are placed after printing.

In carrying out my invention, I employ parallel pairs of endless bands mounted upon suitable pulleys and supported by suitable shafts in bearings upon a bed plate; one band of each pair is wider than the other and each band is provided with series of pins in pairs and the bands of the pairs sustain adjustable relation to one another, to provide for the size of the signatures or sheets to be sewed together to form a book. The bands are associated with support plates in pairs, the same holding up the superimposed signatures between the pins where they pass around at the underside of the endless

bands. The spaces between adjacent series of pins form receptacles to receive the piles of superimposed sheets or signatures as they are laid thereon according to their successive numbers. Each of the pairs of bands provides for a predetermined number of signatures and the one pair of bands may bear a predetermined relation to the other pair of bands in the number of signatures so as to fill up the full quota of signatures for a book in which the signatures are less than the combined capacity of the two pairs of bands.

I provide a suction separator and a gripper device for each pair of bands, a suitable cam-actuated device for raising and lowering the suction separator and other cam-actuated devices for causing the gripper devices to be operated. I also provide swinging arms carrying on their free ends, said gripper devices and means for actuating the same so that each signature lifted from the bands is at once taken by the gripper device and moved forward so as to cause the same to overhang an inclined table onto which the signatures are dropped successively. The gripper device is preferably actuated electrically.

I provide means for successively feeding along the signatures as they are delivered onto the inclined table. I provide means suitably actuated for turning the pairs of bands separately or together, which means are adapted for actuation at any point desired. I also provide means for electrically actuating the aforesaid devices and controlling the same, all of which will be herein-after more particularly described.

In the drawing, Figure 1 is a general plan view representing the device of my improvement. Fig. 2 is a side elevation of the same, some details being omitted which would tend to confuse this figure. Fig. 3 is a side elevation and partial longitudinal section showing the first pair of endless bands, and Fig. 4 is a similar view showing the second pair of endless bands, both figures being on a smaller scale. Fig. 5 is a sectional plan, showing the devices for separately and independently and yet simultaneously actuating the pairs of endless bands with the oscillating parts at the opposite ends of their stroke from that shown in Fig. 2. Fig. 6 is an elevation and diagrammatical view representing the devices for the electric control and operation of the principal devices of my improvement. Fig. 7 is a sectional plan through the shaft line

of the devices shown in Fig. 6. Fig. 8 is a cross section and elevation on the dotted line x, x , of Fig. 5, and Fig. 9 is a cross section on the dotted line y, y , of Fig. 3.

5 Referring particularly to Fig. 2, a represents the bed plate of the machine and the same is provided with bearing pillars in pairs, $a' a' a^2 a^2$, and $a^3 a^3$; the pillars a', a' , are provided with bearings for the shaft b ; the pillars a^2, a^2 , with bearings for the shaft c , and the pillars a^3, a^3 , with bearings for the power shaft d . This power shaft is provided with a pulley d' , whereby it and the devices associated therewith are rotated or otherwise actuated.

Referring to Figs. 1 to 4 inclusive, I provide upon the shaft b the pulleys b', b^2 , and upon the shaft c the pulleys c', c^2 . These shafts are parallel and these pulleys are so placed that the pulleys b', c' are in line and the pulleys b^2, c^2 , are in line. Surrounding these pulleys b', c' , are the endless bands e, f . The band e is appreciably wider than the band f . Surrounding the pulleys b^2, c^2 25 are the endless bands $e' f'$, the band e' being appreciably wider than the band f' . These bands are provided with pins 2 3 in pairs near the opposite edges of the bands and the bands $e' e'$ are at least as much wider than the bands $f' f'$ as the diameter of the bases of the pins. The fact that these bands $f' f'$ are superimposed upon and around the bands $e' e'$ insures a frictional grip between the same sufficient to cause the same to travel together. The one however can be shifted 30 with relation to the other; this act being performed in any desired manner so as to change the relation of the pair of pins of the respective bands in relation to one another, because as shown by dotted lines in Fig. 1, a folded signature comes between the pair of pins 2 of the band f and a pair of pins 3 of the band e . The signatures may be as wide as the distance between the 35 pairs of pins 2 of the bands $f' f'$ in which case the pins 3 of the bands $e' e'$ will align with the pins 2. To adapt the bands to receive smaller sheets they are adjusted by shifting the bands of each pair so as to bring a pair of pins 2 and a distant pair of pins 3 closer together; the piles of superimposed signatures as they are laid above the bands $e f$ or $e' f'$ are longer from the top to the bottom edge of the sheet than the width 40 of the wider bands $e' e'$, consequently the ends project and provision must be made for supporting these signatures below the respective pairs of pulleys. I provide support plates $g h$ in pairs, the main portions 45 of which as will be seen particularly with reference to Figs. 1, 3 and 4, extend below the planes of the lower parts of the bands beyond or outside the line of the pairs of pins 3 and around at the ends of the bands, and said plates are placed not only parallel

with each other but parallel with said bands, their respective ends being semi-circular and their free ends bent outwards, Figs. 3 and 4, at their lower portions showing the superimposed signatures as resting upon these 70 support plates $g h$. These support plates form ways along and over which the superimposed piles of signatures are carried.

Near the outer end of the power shaft d and adjacent to the actuating pulley d' thereof, is a cam wheel i , the same having the cam groove i' in its inner surface. I provide arms k at the opposite sides of the machine connected by pivot pins 4 to the upper ends of the pillars $a' a'$ and the free ends of these 80 are connected by a cross-rod k' .

I provide a roller i^2 secured to one of the arms k movable over the surface of the cam wheel i and thus raising and lowering the arms k and the cross-rod k' . To this cross-rod k' and at predetermined points which come centrally over the centers of the pairs of endless bands, I provide sucker devices $l l'$; these may be of any desired description adapted for the lifting, one at a time, of the 90 signatures from the respective piles upon the endless bands. As illustrated, each of the sucker devices is composed of a casing from which extends a pipe, a contacting surface and a spring arm for holding down the signatures of the piles while the sucker is raising the upper signature at its folded back edge, but I do not limit myself in any respect to the construction of these sucker devices.

The position of the roller i^2 on one of the arms k and the shape of the cam wheel i on the power shaft are so arranged and proportioned as to cause the sucker devices to descend accurately upon each succeeding pile 105 of signatures upon the endless bands as they are presented. I provide an arm m connected by a pivot pin 5 to one of the bearing pillars a' and to the free end of which arm a link m' is pivotally connected. This link m' at its upper end, is connected to a crank m^2 mounted upon the shaft m^3 in bearings at the upper ends of the pillars $a^2 a^2$. This arm m is actuated by the cam groove i' of the cam i acting upon a roller m^5 on said arm m . This shaft m^3 has connected to it arms m^4 in the same vertical planes as the sucker devices and the centers of the pairs of endless bands, and these arms m^4 have an oscillating movement and are provided at 110 their free ends with gripper devices; as shown, each gripper device consists of an electro-magnet 6, gripper fingers 7 and a spring 8. The outer member of the gripper fingers is fixed to the outer end of the arm m^4 and the inner member of the fingers is pivoted near the end of the arm m^4 and it is spring-returned. The opposite end of this pivoted finger device carries an armature 115 to be attracted by the electro-magnet 6 and 120

the movements of these gripper fingers are so timed in relation to the sucker devices that when each successive signature is raised by the sucker devices, these gripper 5 devices are on hand and in position to engage the folded back portion of the signature so as to remove the same from the sucker devices and carry the signatures forward slightly further than the full line 10 position, Fig. 2, in which the free end of the signature passes over the upper end of the inclined table n and when the electric circuit is open and the magnet demagnetized, the gripper fingers open and drop the 15 sheet, the same being caught by the shelf portion of the inclined table and supported thereby.

In connection with the inclined table I provide a pin 9 secured to an endless strap 20 10 which passes around pulleys 11 and 12 mounted upon the lower portion and at the back of the inclined table. The pin 9 passes through a slot made longitudinally of the table, and a backward and forward or reciprocating motion is imparted to this pin by 25 the endless strap 10 and by means of the band wheel n' which is connected to but loosely mounted upon the free end of the shaft c , and an endless belt 16 passing around 30 the band wheel n' and around the pulleys 13 and 14, and also around a pulley 15 which is concentric with the pulley 12 and on the same arbor. The manner of actuating the band wheel n' will be hereinafter more particularly described.

In Figs. 1 and 2, I have shown contact fingers 17 connected to the pillar a' and with their free ends resting upon a make-and-break wheel 18 mounted upon the power 40 shaft d and adjacent to the cam i , there being by preference, electrical connections from and through said contact fingers to the electro magnet 6 and a battery, which are not shown as connected to the gripper devices upon the free ends of the arms m^4 . I have not shown these electrical connections and I do not lay any claim to their arrangement or to the electrically operated gripper fingers actuated thereby.

Referring particularly to Figs. 1 and 5, I provide a sleeve c^3 loose on one end of the shaft c . This sleeve passes through the hub of the pulley c^2 which is secured to it; therefore these parts are free from the rotation 55 of the shaft c . This sleeve c^3 stops at a predetermined point and loose on the shaft c beyond the outer end of the sleeve I provide a structure preferably integral, which comprises the crank o with the crank T head o' . 60 Alongside the crank o a ratchet r is secured upon and adjacent to the free end of the shaft c and the ratchet r' is secured upon the end of the sleeve c^3 see also Figs. 1, 2 and 5. These ratchets $r r'$ have teeth pointing in the 65 same direction for like rotation and it will be

apparent that a movement of the ratchet r will turn the shaft c and the pulley c^2 secured thereto and with the said pulley will move the endless bands $e f$ with their pins; also that a rotation of the ratchet r' will 70 move the sleeve c^3 , the pulley c^2 and turn the bands $e' f'$ which surround the same and the pulley b^2 and that these movements may be independent of one another or simultaneous.

On the power shaft d I provide a short crank 75 d^2 and a connecting rod 23 is at one end mounted upon this crank and at the other end is connected to the longer crank o and by these devices the crank o and its T head o' are given a swinging or oscillatory movement, the crank d^2 performing complete revolutions. On this T head o' are mounted electro-magnets $s s'$ in pairs and pins 19 and 20 pass through the T head between the electro-magnets of the pairs, the inner ends of 85 said pins being adapted to come in contact with the surfaces or peripheries of the ratchets $r r'$ and having pins through them on the inner side of the T head to limit their outward movement. These pins are provided 90 with armatures 21 22 adapted to be attracted by the poles of the electro-magnets; the pins between the head o' and the armatures are provided with helical springs which tend to push the armatures away from the cores of 95 the electro-magnets, the attraction of the electro-magnets when the circuit is closed being to draw down the armatures to the poles of the magnets as against the resiliency of the springs surrounding said pins; consequently in one position, (see Fig. 5) the pin 100 20 is drawn down into the path of and against the surface of the ratchet r' whereas the pin 19 is forced away by the spring so that it is out of contact with the surface of 105 the ratchet r' . A pin n^2 connects the crank T head o' at one end with the band wheel n' so that this band wheel moves with the movement of the T head and not otherwise and as the T head is swung or oscillated by the 110 action of the cranks o, d^2 and connecting rod 23, this T head is moved back and forth through a quarter of a revolution, moving with it the band wheel n' , and belt 16 and turning the pulleys 11 and 12, their endless strap 10 reciprocating its pin 9, so that as the signatures are delivered by the gripper devices at the ends of the arms m^4 on to the inclined table n , they are moved by this pin 9 from their position of delivery forward 115 and along the inclined table to a position convenient for the operator of the book sewing machine to take the said signatures and opening the same, place them upon the sheet holding bar.

Referring particularly to Figs. 6 and 7, and to the upper portion of Fig. 1, showing the parts in plan,—24 is a standard to which a stud 25 is secured. 26 is a base carrying this standard and also carrying posts 27 and 120 125 130

28. The power shaft d is provided with a cam d^3 , the surface of which acts upon the roller t^2 of a pawl arm t , which is pivotally mounted upon the stud 25 and which carries a pawl t' spring actuated. I provide a stop pin t^3 secured to a suitable fixed point and adapted for lifting the pawl from the teeth of the ratchet v and a spring 29 which extends from the posts 28 to the pawl arm t , 10 the function of which is to hold the roller t^2 of this pawl arm against the periphery or surface of the cam d^3 . With the ratchet v preferably in an integral structure, is formed a cam wheel v' and there is a recess between 15 this ratchet and cam wheel receiving the cord 53 of a weight 52, the function of the cord and weight being to cause the rotation of this ratchet and cam wheel in a direction opposite to the direction imparted to it by 20 the pawl t' and pawl arm t . I provide a pin 30 on the ratchet v and a pin 31 on the cam wheel v' in the positions shown in Fig. 6, and v^2 is a removable cam wheel mounted on the stud 25 but particularly on a sleeve 25 of the ratchet and cam structure v v' , as will appear from the section Fig. 7. This cam wheel v^2 is smaller than the cam wheel v' and is interchangeable with other cam wheels of different diameters and character 30 of peripheries. The cam wheel v' bears an operative relation to the series of signature holders of the endless bands e f , while the removable cam wheel v^2 bears an operative relation to the signature holders of the endless bands e' f' , as will be hereinafter more 35 particularly described. 32 represents a pawl and 33 a catch arm preferably formed integral or upon the same shaft and pivotally mounted in a post 34, the pawl 32 engaging 40 the teeth of the ratchet v and being provided with an armature to be attracted by the electro magnet 35, which is mounted upon the post 28, there being a spring from the arm 33 to the base of the post 28, the function 45 of which is to hold down the arm 33 and to throw the pawl 32 into engagement with the teeth of the ratchet v . I provide a bell crank arm 36 mounted in a post upon the base 26, in which base is a pin shown in 50 Fig. 6 to prevent the upper movement of the bell crank arm by a spring shown under the same, and at 37 I have shown an insulated contact on the forward end of the lower member of this bell crank arm 36. 38 55 is an insulated contact finger secured to the base 26. 39 and 40 are pivoted gravity bars with curved or hook-ended free ends. These arms are pivotally mounted in the post 27 and they are each provided with insulated 60 contacts adapted to make and break the electric circuit with the insulated bracket arms 41 42 which are mounted upon the post 27. From Fig. 6 it will be noticed that the circuit is broken between the bar 39 and 65 the bracket arm 41, while the circuit is made

between the bar 40 and the bracket arm 42, and this is because the free end of the bar 39 rests upon the surface of the cam wheel v' of shortest radius while the free end of the bar 40 rests upon the surface of the cam 70 wheel v^2 of greatest radius. 43 is a battery, see Fig. 6. 44 is a wire which extends from the finger 38 to the electro magnet 35; 45 a wire which extends from the electro magnet 35 to the electro-magnet s' ; 46 a wire which 75 extends from the gravity bar 40 to the electro-magnet s' . 47 is a wire that extends from the bracket arm 42 to the battery 43 and a short wire connects the other pole of the battery 43 with the wire 48. This wire 80 48 extends from the wire 45 to the electro-magnet s . 49 is a wire which extends from the other side of the electro-magnet s to the gravity bar 39. 50 is a wire which extends from the bracket arm 41 to connection with the wire 47 and electrically to the bracket arm 42. 51 is a wire which extends from the insulated contact 37 on the bell crank arm 36 to connection with the wire 47.

In the operation of the devices hereinbefore described, the power shaft d is rotated by a pulley d' . The cam wheel i through the roller i^2 raises and lowers the arms k and the sucker devices which lift a signature at a time from between the pins on the endless bands e f , e' f' . The rotation of this cam wheel i and its groove i' through the roller m^5 therein on the arm m actuates the link m' , the crank m^2 and the shaft m^3 , and the gripper devices in time with the sucker 95 devices to remove the signatures from the sucker devices and carry the same over the upper end of the inclined table n and drop them thereon when the electrically actuated gripper fingers will open as hereinbefore described. The rotation of this power shaft d actuates the crank d^2 and cam d^3 and with the crank d^2 , the crank rod 23, the crank o and its T-head o' and the devices mounted upon this T-head. The teeth of 100 the ratchet v are numbered from one consecutively to the end in the direction of rotation; there are as many teeth as there are signature receptacles on the two pairs of endless bands and the parts are so arranged 105 and timed that the signatures are taken progressively from their receptacles as the pawl arm t and its pawl t' by the action of the cam d^3 moves the ratchet v a tooth at a time; the cam d^3 rotates with the power shaft d 110 in unison with the cam i and once for each operation of the sucker and gripper devices consequently the pawl arm t is moved back by the spring 29 sufficiently for the stop pin t^3 to throw up the point of the pawl out of 115 the path of the teeth of the ratchet v , and as the pawl arm is each time moved by the cam d^3 , the pawl t' engages another tooth of the ratchet v , turning the same to that extent. 120

It is to be understood that the length of 130

the depressed portion of the cam-wheel v^2 is governed by the number of signature receptacles unused in the conveyer $e^1 f^1$ and the period during which the circuit to the electro-magnet s^1 is broken. The sucker devices are provided with the usual means for their actuation, the same not being herein shown or described.

In the operation of the device and with reference to Fig. 3, the signatures have been lifted from the compartments between the pins of the endless band conveyer $e f$, from number 1 to 10 inclusive, which completes the cycle of these signatures; while the ratchet v has been moved a tooth at a time progressively over 10 teeth with the gravity bar 39 resting upon the portion of the wheel v^1 of greatest radius. At the end of this cycle of movements the gravity bar 39 passes with the rotation of the ratchet v , cam-wheel v^1 and cam-wheel v^2 from the part of the wheel v^1 of greatest radius to the part of least radius, breaking the electric circuit between the bar 39 and the bracket arm 41, and the electro-magnet s being demagnetized, the spring on the pin 19 moves said pin longitudinally, carrying the armature from the cores of the magnet and its free end away from the path of the ratchet r ; therefore this ratchet r and the shaft c come into a state of rest. Simultaneous with this movement the rotation of the cam-wheel v^2 raises the bar 40 from the lower or depressed surface of the cam-wheel v^2 onto its surface of greatest radius and closes the circuit through the bracket-arm 42, through the wires 46, 47, battery 43 and the wire 45, and through the electro-magnet s^1 , energizing the same and drawing down the armature 22 and so pushing the pin 20 into the path of the ratchet r^1 so that the oscillating movement imparted by the crank-rod 23 to the crank T -head o^1 causes the rotation of the ratchet r^1 a tooth at a time and imparts a rotation to the sleeve c^3 , the pulleys c^2 and b^2 and the endless band conveyer $e^1 f^1$, so that the sucker devices and the gripper fingers commence on a pile of signatures 11 and so on successively to the completion of the sixteen signatures shown in Figs. 3 and 4.

By reference to Fig. 6, it will be noticed that the pawl t^1 is in engagement with the fourteenth tooth of the ratchet v , and by reference to Fig. 4 the top signature of the pile of signatures 14, is in the position it would occupy after the removal of a signature therefrom. The ratchet-wheel v is now turned two more teeth and the compartments 15 and 16 are successively moved into position and the signatures taken therefrom. At the completion of this movement the cam d^2 has turned in the direction of its rotation as indicated in Fig. 6, so that the backward movement of the pawl-arm t with its pawl t^1 is sufficient for the latter to strike the

stop pin t^3 and be raised out of contact with the teeth of the ratchet-wheel v . Simultaneously with this movement the pin 31 has been brought into contact with the bell crank-arm 36 and turning the same completes the electric circuit through the contact 37 and arm 38 from the wires 47 and 51 through the wire 44 and electro-magnet 35, thus drawing over the pawl 32 and releasing the ratchet v and cam-wheels $v^1 v^2$. The weight 52 then becomes operative and through its cord 53 turns these parts backward until the pin 30 on the ratchet v strikes the catch of the arm 33 and moves the same so as to return the pawl 32 into engagement with the teeth of the ratchet. This return movement will of course have moved the pin 31 causing the bell crank-arm 36 to be returned by its spring to its initial position, breaking the electric circuit through the electro-magnet 35 so as to release the pawl 32 and prepare it to be swung into engagement with the teeth of the ratchet v when the pin 30 strikes the catch of the arm 33. This movement will bring the ratchet v around into position so that the pawl t^1 will with the timed advance rotation of the cam wheel d^3 engage the first tooth. At the completion of this return movement, the free ends of both gravity bars 39 and 40 will rest upon the peripheries of the cam wheels $v^1 v^2$ of greatest radius ready to commence anew the movements described. The gravity bar 39 with its free end on the portion of the cam wheel v^1 of greatest radius completes the circuit through the wire 49, bracket arm 41, wires 50 47, battery 43, wire 48 and electro-magnet s so as to bring the pin 19 into the path of the ratchet r to turn the same a quarter of a revolution at a time and thereby turn the shaft c , pulleys $c^1 d^1$ and impart a step-by-step movement to the endless band conveyer $e f$ and the piles of superimposed signatures thereon; the sucker and gripper devices hereinbefore described being in operative position to remove the signatures one at a time from the piles of signatures on the said band conveyer $e f$ from number 1 to number 10 inclusive. While the ratchet v is being turned by the pawl t acting on the first ten teeth the bar 39 is upon the part of the cam wheel v^1 of largest radius and during this period the circuit to the electro-magnet s is closed to move the conveyor $e f$ so that the signatures may be successively taken from the ten receptacles thereof. While the first part of this movement is taking place the gravity bar 40 remains upon the surface of the wheel v^2 of greatest radius, closing the circuit as hereinbefore described to the electro-magnet s^1 , pulling the pin 20 down into the path of the ratchet r^1 so that the conveyer $e^1 f^1$ is also and simultaneously moved the distance of its four empty receptacles step-by-step with

the conveyer $e^1 f^1$ and then the conveyer $e^1 f^1$ is stopped while the conveyer $e^1 f^1$ moves the six other step-by-step movements required to bring its number 10 receptacle into place 5 where the signature is removed therefrom. The conveyer $e^1 f^1$ is stopped for this period because the gravity bar 40 with the rotation of the ratchet and cam-wheels moves off the portion of the periphery of the cam-wheel 10 v^2 of greatest radius onto the part of lesser radius.

It will be further noticed from Fig. 6, that when the gravity bar 40 moves up onto the part of the wheel v^2 of greatest radius 15 completing the circuit the bar 39 simultaneously moves off the part of the wheel v^1 of greatest radius, breaking the other circuit. Simultaneously the conveyers $e^1 f^1$ are arrested and the conveyers $e^1 f^1$ moved so that the 20 signatures, numbers 11 to 16 may be taken therefrom. The completion of this movement brings the parts to the position where the pin 31 strikes the bell crank lever 36 to effect the return movement of the parts to 25 an initial position as hereinbefore described.

I have not herein shown nor described any devices adapted for the operation of the suckers. It is of course essential that suitable mechanism for this purpose be provided; the same however, forms no part of 30 my present invention. This mechanism may be any well-known valve mechanism, pump, etc., adapted for actuating these sucker devices at any time and in any order. These 35 devices will of course be arranged for the operation of the sucker devices as and when required, so as to remove the signatures progressively as desired, or permit the sucker devices to inactively contact therewith and 40 not remove the same when necessary. It will therefore be noted that while signatures are being removed from the compartments 11 to 16 of the conveyer $e^1 f^1$, such mechanism is inactive with regard to the sucker device employed in connection with the conveyer $e^1 f^1$ and while the sucker device is 45 active in removing the signatures from the conveyer $e^1 f^1$ the other sucker device employed in connection with the conveyer $e^1 f^1$ 50 is inactive.

In like manner as hereinbefore described, the operations are repeated.

While I have described my invention with special reference to the feeding and assembling of signatures, it is obvious that the devices shown and described are adapted for use equally well for feeding and assembling such equivalents as single sheets, cards, covers, etc. or single sheets alternated with 55 signatures without in any manner departing from the nature and spirit of my invention.

I claim as my invention:

1. In a machine for feeding signatures, the combination with a signature-conveyer 60 adapted to receive piles of superimposed sig-

natures and means for maintaining said piles separate, of devices for successively taking a signature at a time from each of said piles, a gripper for taking the signature from said devices and a receptacle upon 70 which the signatures are delivered.

2. In a machine for feeding signatures, the combination with a conveyer adapted to receive piles of superimposed signatures and means for maintaining said piles separate, 75 of a sucker device for successively taking a signature at a time from said piles, a gripper device for taking the signatures from the sucker device and a receiving device upon which the signatures are delivered one 80 at a time.

3. In a machine for feeding signatures, the combination with a conveyer adapted to receive piles of superimposed signatures and means for maintaining said piles separate, 85 of a sucker device for successively taking a signature at a time from said piles, and a gripper device for taking the signatures from the sucker device, a receptacle upon which the signatures are delivered one at a 90 time, and pusher mechanism for moving the signatures one at a time along upon the latter receptacle.

4. In a machine for feeding signatures, the combination with a signature conveyer 95 adapted to receive piles of signatures and means for maintaining said piles separate, of devices for successively taking a signature at a time from said piles, means for taking the signatures one at a time from 100 said devices and a receiving device upon which the signatures are delivered one at a time.

5. In a machine for feeding signatures and in combination, separate signature conveyers, means for imparting to said conveyers step by step movements in a predetermined order, means for maintaining the piles of signatures on the conveyers separate from one another, devices for successively taking a signature at a time from said piles, 110 means for taking the signatures from said devices and a suitable receptacle upon which the signatures are delivered.

6. In a machine for feeding signatures 115 and in combination, separate signature conveyers, means for imparting to said conveyers step by step movements in a predetermined order, means associated with said signature conveyers for maintaining the piles 120 of superimposed signatures separate from one another, sucker devices for successively taking a signature at a time from the piles of signatures on the actuated conveyer, means for taking the signatures from the 125 sucker devices and a suitable receptacle upon which the signatures are delivered.

7. In a machine for feeding signatures and in combination, separate signature conveyers, means for imparting to said signa- 130

ture conveyers step by step movements in a predetermined order, means associated with said signature conveyers for maintaining the piles of superimposed signatures separate from one another, sucker devices for successively taking a signature at a time from the piles of signatures on the actuated conveyer, means for taking the signatures as delivered from the sucker devices, an inclined table receiving the signatures one at a time from the latter mechanism and pusher mechanism for moving the signatures along over the face of the inclined table.

8. In a machine for feeding signatures and in combination, two parallel conveyers adapted to receive piles of superimposed signatures and means for maintaining said piles separate, means for actuating the conveyers, a power shaft, a wheel on said power shaft having a cam surface and cam groove, sucker devices adapted for successively taking a signature at a time from the piles upon the conveyers and means for actuating the sucker devices from the cam surface of said wheel, gripper devices for receiving the signatures one at a time from the sucker devices and means for actuating the same by means of the cam groove and a table for receiving the signatures in an inclined position.

9. In a machine for feeding signatures and in combination, sucker and gripper devices and actuating means therefor parallel and independent conveyers, a shaft therefor, a concentric sleeve upon one end of the conveyer shaft, a ratchet on the shaft and another ratchet on the sleeve, said ratchets being spaced apart from one another, a crank and crank T head mounted on the shaft between the ratchets, a power shaft and crank thereon and a crank rod connecting the two cranks for imparting motion to the crank T head from the power shaft, devices connected to the T head and means for actuating the same whereby either or both of said ratchets are engaged to operate either or both of the conveyers.

10. In a machine for feeding signatures and in combination, sucker and gripper devices and actuating means therefor parallel and independent conveyers and a shaft therefor, a concentric sleeve upon the conveyer shaft, a ratchet on the shaft, and another ratchet on the sleeve, said ratchets being spaced apart from one another, a crank and crank T head mounted on the shaft between the ratchets, a power shaft and crank thereon and a crank rod between the two cranks for imparting motion to the crank T head from the power shaft, spring actuated pins passing through the T head, the points of which as pawls are adapted to engage the ratchet, armatures mounted on the ends of said pins, electro-magnets mounted on the T head and adapted for the actuation of the

said pins and means for making and breaking electrical circuits through said magnets so as to control the movements of said pins.

11. In a machine for feeding signatures and in combination sucker and gripper devices and actuating means therefor parallel and independent conveyers and a shaft therefor, a concentric sleeve upon which the pulleys at the other ends of the conveyers are secured, a ratchet on the shaft and another ratchet on the sleeve, said ratchets being spaced apart from one another, a crank and crank T head mounted on the shaft between the ratchets, a power shaft and crank thereon and a crank rod between the two cranks for imparting motion to the crank T head from the power shaft, spring actuated pins passing through the T head, the points of which as pawls are adapted to engage the ratchet, armatures mounted on the ends of said pins, electro-magnets mounted on the T head and adapted for the actuation of the said pins, a cam wheel on the power shaft, a pawl arm spring controlled actuated thereby, a ratchet wheel having teeth which agree in number with the spaces of the endless conveyers receiving piles of superimposed signatures, and which ratchet wheel is actuated by the pawl of said pawl arm, cam wheels adjacent to the said latter ratchet and electrical devices actuated thereby for making and breaking electric circuits through the armatures of said T head for controlling the movements of the ratchet wheels operating the endless band conveyers.

12. In a machine for feeding signatures and in combination sucker and gripper devices and actuating means therefor parallel and independent conveyers and a shaft therefor, a concentric sleeve upon which the pulleys at the other ends of the conveyers are secured, a ratchet on the shaft and another ratchet on the sleeve, said ratchets being spaced apart from one another, a crank and crank T head mounted on the shaft between the ratchets, a power shaft and crank thereon and a crank rod between the two cranks for imparting motion to the crank T head from the power shaft, devices connected to the T head, means for actuating the same whereby either or both of said ratchets are engaged to operate either or both of the conveyers, a cam on the power shaft adjacent to the crank thereon, a spring actuated pawl and pawl arm and stud upon which the same are mounted actuated by said cam, a ratchet on said stud, the teeth of which agree in number with the piles of superimposed signatures which the endless conveyers are adapted to carry, pins on said ratchet limiting the movements thereof in opposite directions, cam wheels on said stud and electric devices and connections therefrom adapted to control the extent of movement of the respective endless conveyers, a

pawl and actuating device for holding the latter ratchet in position, an electro-magnet for turning the same away and releasing the ratchet, electrical devices through which the 5 circuit is established by one of said pins for demagnetizing said electro-magnet and releasing said pawl, and means engaged by the other of said pins for restoring said pawl to engagement with the ratchet and mechanical devices actuated in the interim for turning back the said ratchet to its initial position.

13. In a machine for feeding signatures and in combination, signature conveyers, 15 sucker and gripper devices, means for actuating the same, a ratchet v and cam wheel v^1 , a removable cam wheel v^2 , and electrical devices co-acting with the ratchet and cam-

wheels for controlling the movements of the signature conveyers.

14. In a machine for feeding signatures and in combination, signature conveyers, sucker and gripper devices, means for actuating the same, mechanical devices to which a step by step movement is imparted, 20 means actuating the conveyers therefrom and in unison therewith, and electrical devices for controlling the mechanical devices, whereby either or both of said conveyers may be progressed to the desired extent. 25

Signed by me this 20th day of August 1907.

DAVID G. SMYTH.
